UNITED STATES PATENT OFFICE

CHARLES OPPE, OF NEW HAVEN, CONNECTICUT, ASSIGNOR TO THE G & O MANUFACTURING COMPANY, OF NEW HAVEN, CONNECTICUT

ENGINE-COOLING RADIATOR

Application filed July 21, 1926. Serial No. 124,052.

This invention relates to radiators for internal combustion engines, and more especially to the construction of the filler neck usually attached to the upper tank of such a 5 radiator, and to the means for attaching the overflow or vent tube to the upper tank so that it will be held securely in proper position to perform its function.

A radiator used for cooling internal combustion engines ordinarily consists of upper and lower fluid tanks connected by a series 10 of tubes or water channels which form the cooling section of the radiator. An overflow or vent tube is ordinarily secured in the 15 upper tank, the open upper end of this tube usually being disposed within the filler neck so that, while this tube permits the radiator to be filled to its capacity, it will, when the fluid expands upon being heated permit the 20 excess fluid to drain off so that it will not overflow about the radiator cap. The lower end of the overflow tube is usually passed through the wall of the radiator tank so that the excess fluid is vented upon the ground.

25 One object of this invention is to provide a novel means of securing the filler neck to the upper tank of the radiator.

Another object of the invention is to provide a radiator with a vent tube or overflow 30 pipe secured thereto in such a manner that the same will not become detached or broken in service.

A further object of the invention is to 35 provide a novel and economical method of securing the vent tube or overflow pipe to the radiator filler neck.

Still another object of the invention is to 40 provide an improved means for securing the overflow or vent tube in place against the wall of the filler neck of the upper tank of the radiator so firmly that it will not be displaced in use, and at the same time provide a connection of this character which may be 45 economically and cheaply made.

To these and other ends the invention consists of the novel features and combination of parts to be hereinafter described and claimed.

50 In the accompanying drawings:

Fig. 1 is a front elevational view of a radiator for internal combustion engines embodying my improvements;

Fig. 2 is an enlarged sectional view 55 through the filler cap of the radiator taken on line 2—2 of Fig. 3;

Fig. 3 is a sectional view on line 3—3 of Fig. 2;

Fig. 4 is an enlarged sectional view through 60 the upper filler neck of the radiator taken on line 4—4 of Fig. 5 and showing a modified form of my invention;

Fig. 5 is a sectional view on line 5—5 of Fig. 4.

The radiator which I have selected to illustrate as embodying my improvements comprises an upper tank 10, a lower tank 11, between which is the usual cooling section 12. Upon the upper tank 10, and communicating with the interior thereof, is a filler tube 13 70 which is threaded at 14 to receive the usual cap 15.

Referring to Fig. 2, it will be seen that the radiator tank 10 is provided in its upper surface with an opening surrounded by a flange 75 16, the flange being turned upwardly from the metal of the tank so that it assumes a substantially vertical position. The lower end of the neck or tube 13 is inserted within this flange, and is of such a size as to fit fairly snugly therein so that a soldered connection may be made between these two parts to effect a water-tight joint; that is, after the lower end of the filler tube has been inserted within the flange 16 the space between the neck 80 and the flange may be effectually filled with solder so that all danger of leakage is obviated.

As shown in Fig. 1, an overflow or vent tube 17 is disposed within the upper tank of the 90 radiator, the upper end 18 of this tube extending to a point within the filler neck and adjacent the top thereof. The lower end 19 of this tube extends without the radiator so that it may discharge the excess fluid upon 95 the ground.

In order to secure the upper end of the tube 17 in place against the side wall of the filler neck 13, a loop 20 is struck out from the metal adjacent the lower end of the filler neck in 100

such a manner that the tube 17 may be inserted between this loop and the side wall of the neck. It will be noted that the loop 20 is of relatively narrow width, and that the overlap between the lower end of the filler neck 13 and the flange 16 is of sufficient width so that when this loop is struck out from the neck sufficient material 22 will remain to make a tight joint with the flange 16 adjacent the loop.

With this construction I am enabled to use a portion of the metal of the filler neck itself to hold the vent tube in position, and at the same time make a tight connection between the neck and the upper tank of the radiator so that there is no danger of leakage. The tube 17 fits snugly between the loop 20 and the side wall of the filler neck so that it will be held securely in position and will not be displaced by the shocks to which it may be subjected in use. In practice the tube will usually be secured by solder to the loop 20.

In Figs. 4 and 5 of the drawings I have shown a somewhat modified form wherein the upper tank 10 of the radiator is provided with a flange 16 surrounding the opening for the filler tube, as has already been described. The lower end of the filler neck 13 is likewise received within this flange and soldered thereto. In this instance, however, the filler neck is inserted into the upper tank before the soldering operation to a sufficient distance to allow a tongue 23 to be struck up from the wall of the filler neck at the lower end thereof to a position at substantially right angles to this wall, the width of the tongue 23 being of such a dimension that it may be provided with an opening 24 through which the tube 17 may be inserted. It will be noted that the junction 25 of the tongue 23 with the wall of the filler neck is disposed at a substantial distance below the upper edge 26 of the flange 16, so as to permit a sufficient overlap of this flange and the side wall of the filler tube to make a tight joint when the solder is applied between these two parts.

I am enabled in this construction also to use a part of the metal of the filler neck to embrace the vent tube and secure it in place, and at the same time leave sufficient overlap between the filler tube and the flange upon the upper radiator tank to make a water-tight joint in the manner described. It will also be apparent that the vent tube will be held firmly in place and will be held closely against the wall of the filler neck so that it will not ordinarily interfere with the filling of the radiator; that is, when the radiator is being filled no appreciable part of the water will enter this tube.

While I have shown and described some preferred embodiments of my invention, it is to be understood that it is not to be limited to all the details shown but is capable of modi-

fication and variation within the spirit of the invention and within the scope of the appended claims.

What I claim is:

1. A radiator for internal combustion engines having a tank provided with an opening in its upper side, a filler neck connected with said opening and extending upwardly from the tank, a vent tube within the tank having its upper end extended in the filler neck adjacent the wall thereof and means integrally formed with the filler neck and embracing the vent tube to hold it snugly against the wall of the filler neck. 70 75

2. A radiator for internal combustion engines having a tank provided with an opening at its upper side and a filler neck extending upwardly from said opening, a vent tube having its end extending from the tank within said filler neck and a part of the metal of the filler neck being displaced inwardly to engage the remote side of the vent tube and secure it in place. 80 85

3. A radiator for internal combustion engines having a tank provided with an opening in the upper side thereof, and a filler neck extending upwardly from said opening, a vent tube having its upper end extending within the filler neck adjacent the wall thereof, the metal of said filler neck at the lower end thereof being displaced inwardly to provide means to embrace the vent tube and hold it in place. 90 95

4. A radiator for internal combustion engines having a tank provided with an opening in the upper side thereof, and a filler neck secured to the tank within said opening, a vent tube having its upper end extended within the filler neck and adjacent the wall thereof, the metal of said filler neck at the lower end thereof being displaced inwardly to provide means to embrace the vent tube and hold it in place. 100 105

5. A radiator for internal combustion engines, having a tank provided with an opening in the upper side thereof, and a filler neck secured to the tank within said opening, a vent tube having its upper end extended within the filler neck and adjacent the wall thereof, and means formed integrally with the filler neck and embracing the vent tube to hold it snugly against the wall of the filler neck. 110 115

6. A radiator for internal combustion engines having a tank provided with an opening, a filler neck having its lower end extending into said opening, a vent tube extending into the filler neck adjacent the side wall thereof, and the metal of the filler neck at the lower end thereof being displaced inwardly so that the end of the vent tube may be received between the displaced portion and the side wall of the filler neck. 120 125

7. A radiator for internal combustion engines having a tank provided with an open- 130

ing at its upper side and a flange surrounding said opening, a filler neck having its lower end telescopically received within said flange and there secured, a vent tube having its end extending within said filler neck from the tank, and a part of the metal of the filler neck within the tank being displaced inwardly to engage the remote side of the vent tube and secure it in place.

10 8. A radiator for internal combustion engines having a tank provided with an opening at its upper side, and a flange surrounding said opening, a filler neck having its lower end telescopically received within said flange and there secured, a vent tube having its end extending within said filler neck from the tank, and said filler neck having a loop struck inwardly therefrom at the lower end thereof to embrace the vent tube and secure it in place.

15 9. A radiator for internal combustion engines having a tank provided with an opening at its upper side, and a flange surrounding said opening, a filler neck having its lower end telescopically received within said flange and there secured, a vent tube having its end extending within said filler neck from the tank, and said filler neck having a loop struck therefrom at the lower end thereof whereby the vent tube may be received between this loop and the side wall of the neck and held snugly against said side wall.

20 10. A radiator having a tank provided with an opening at its upper side, and a vertically disposed flange surrounding said opening, a filler neck having its lower end received telescopically within said flange, the flange overlapping the lower end of the neck, said neck having a loop struck inwardly therefrom below the upper edge of the flange, and a vent tube extending into the neck and disposed between said loop and the side wall of the filler neck.

25 In witness whereof, I have hereunto set my hand this nineteenth day of July, 1926.

CHARLES OPPE.
